UNITED STATES PATENT OFFICE.

ERICH KASTEN, OF MANNHEIM, BADEN, GERMANY.

PNEUMATIC MALTING APPARATUS.

SPECIFICATION forming part of Letters Patent No. 409,151, dated August 13, 1889.

Application filed September 18, 1888, Serial No. 285,673. (No model.) Patented in Germany June 22, 1888, No. 48,366, and in Austria-Hungary November 20, 1888, No. 27,742 and No. 46,384.

To all whom it may concern:

Be it known that I, ERICH KASTEN, engineer, subject of the Emperor of Germany, residing at Mannheim, in the Grand Duchy of 5 Baden, in the Empire of Germany, have invented certain new and useful Improvements in Pneumatic Malting Apparatus, for which I have obtained Letters Patent in Austria dated November 20, 1888, No. 27,742; in Hun- 10 gary dated November 20, 1888, 46,384, and in Germany dated June 22, 1888, No. 48,366; and I do hereby declare the following to be a full, clear, and exact description of the invention, such as will enable others skilled in 15 the art to which it appertains to make and use the same, reference being had to the accompanying drawings, and to letters or figures of reference marked thereon, which form a part of this specification.

20 Referring to the drawings, Figure 1 is a sectional elevation of a malting-house. Fig. 2 is a longitudinal vertical section of a portion thereof, and Fig. 3 is a like horizontal section illustrating my improvements. Fig. 4 is 25 a vertical transverse section of two adjacent malting-floors and part of the mechanism for elevating such floors, as well as of the mechanism for transferring the contents from one 30 floor to another, one of said floors being shown in its elevated position. Fig. 5 is a vertical longitudinal section of one of the malting-floors and the elevating mechanism. Fig. 6 is a side elevation of some of the floors 35 and the elevating and transferring mechanisms; and Fig. 7 is a top plan view of the same, shown partly in section.

The invention relates to the art of malting, and has for its object to provide means whereby the various manipulations of the 40 grain during the process may be effected mechanically, and whereby such process of malting is improved and accelerated by the use of moist and dry air, according to the condition of the grain.

45 To these ends the invention consists in the construction and relative arrangement of the malting-floors, in malting-floors adapted to be elevated so that the contents thereof may be readily discharged onto the malting-floor 50 next adjoining, in the mechanism for elevat- 55 ing the malting-floor, in the mechanism for

transferring the grain from one floor to another, and in structural features, combinations of parts, and details, substantially as hereinafter described, and as set forth in the 55 claims.

The invention further consists in a substantially air-tight malting-chamber, a plurality of adjacent perforated malting-floors, a suction-chamber below each of said floors, 60 and an air-supply duct provided with a valved outlet-port for each of the said floors, in combination with an air-exhaust duct and a branch duct for connecting each suction-chamber with said exhaust-duct, and a valve 65 in each of said branch ducts, substantially as hereinafter described, and set forth in the claims.

Before describing the invention in detail I would state that the malting-floors are ar- 70 ranged in the malting-chamber in two rows; that all of said floors are movable vertically, except the last floor of each row; that the withering-floors are also stationary and are preferably inclosed by masonry, one of the 75 walls thereof being formed by the partition X, that separates the malting-floor from the withering-chamber; that the inclosing-walls of all the malting-floors, movable or stationary, are constructed of sheet metals, as are 80 the floors themselves, as well as the withering-floors; that trap-valves are arranged to close hermetically ports formed in said partition-walls X, for transferring the grain from the last malting-floor to the withering-floor—trap- 85 valves which I have deemed unnecessary to show, as the construction of such is well known, said valves being provided with means for opening and closing the same by hand; that under each of the malting-floors, as well 90 as under the withering-floors, a chamber e' is formed; that there is a portable or traveling mechanism provided for each row of malting-floors for elevating said floors and transferring the contents thereof from the elevated 95 floor to the next floor thereto; and, finally, that there is one or more steeping vats or tubs for each row of malting-floors, so arranged that the steeped grain therein may be transferred to the first malting-floor of each row. 100

In the drawings, H indicates the malt-house, of appropriate construction; A, the malting-

chamber; B, the withering-chamber; I to XVII, the movable malting-floors of a row; XVIII, the last or stationary malting-floor of each row; and XIX, the withering-floors arranged, respectively, in said malting-chamber A and withering-chamber B.

On the upper floors of the malt-house are located the steeping-vats D, provided with ducts D', for conveying the steeped grain to the malting-floors I. The chambers e', below the malting-floors I to XVIII, are in communication with an air-exhaust duct E, arranged between the two rows of floors by means of branch ducts e, the corresponding chambers of the withering-floors being likewise connected to said duct E by means of branch ducts e³ e⁴, (shown in dotted lines in Fig. 3,) the duct E being provided with suitable ports e⁴, Fig. 2. Each duct e of the movable malting-floors is provided with a gravity-valve a', Fig. 5, whose stem a² lies in the path of a lug or rod 9, depending from the under side of the frame of said malting-floors, so that as the floor is elevated the valve will automatically close, while as the floor returns to its normal position the actuating-rod 9 will impinge upon the valve-stem a². The object of this arrangement is to prevent the passage of air through the grain on the malting-floor while said floor is being elevated and during the transfer of the grain thereon to another floor.

The ducts e of the stationary malting-floors, as well as the ducts e³ or the duct e⁴ of the withering-floors, are similarly provided with valves or dampers, (not shown,) and adapted to be operated by hand to regulate the exhaust of the air, or, in other words, to regulate the volume of air drawn through the grain on the said floors, the duct E being connected with a suitable exhaust apparatus.

To still further regulate the exhaust of the air, I provide at the opposite ends of the ducts e dampers e², Fig. 1, by means of which the communication between any one of the chambers e' of the movable malting-floors may be cut off when necessary.

The air supplied to the withering-chamber B may be taken directly from the outer air, if of proper temperature, or such air may be previously brought or reduced to the required temperature by heating or cooling, as the case may be; or, if desired, the waste air from the malt-kilns may be utilized in the withering-chamber.

The air supplied to the malting-chamber is drawn by the exhauster from a chamber or turret C into a distributing-duct F, that extends the full length of the malting-chamber A between the rows of malting-floors, said duct f being provided along its opposite sides with ports y, equal in number to the number of malting-floors, said ports being provided with valves or dampers (not shown) for regulating the amount of air admitted to the malting-chamber. The air drawn in from turret C is preferably made to pass first into a duct or chamber F', for the

purpose of purifying and moistening said air, water being injected in a fine spray into said chamber or duct F'.

In practice I arrange at each of the ports y of the duct F a spraying device or atomizer for the purpose of moistening or further moistening the air drawn in, suitable means being provided for drawing off any surplus water not absorbed by the air. I have deemed it unnecessary to show these spraying devices in the drawings, as such are well known in the arts, and as I do not desire to claim these otherwise than as a mere element in combination with the air-duct F and its ports.

The transferring of the grain from malting-floor to malting-floor is effected by first elevating a malting-floor above the level of the malting-floor next adjacent thereto and then transferring the grain from said elevated floor onto the next below.

The mechanism for elevating the malting-floors and for transferring the grain is supported from a carriage G, mounted on wheels and traveling on rails g', supported by standards G', arranged on opposite sides of the two rows of malting-floors. Thus in operation the steeped grain is fed or dumped from the steeping-vats D onto the malting-floors I. After remaining there an appropriate time these floors are elevated and the contents transferred to floors II, and a fresh charge of steeped grain being then fed to floors I, the grain being thus transferred from floor to floor until all the floors are charged, the grain from the last floor XVIII being transferred to the withering-floors XIX in chamber B, and when all the floors are supplied the process becomes a continuous one, as will be readily understood.

The movable malting-floors are each composed of a supporting-frame 1 of iron girders bolted together, to which is secured a perforated floor 2, preferably of sheet metal, said floor being inclosed on three sides by vertical walls 3 3^a 3^b, Fig. 5, the fourth or one of the longitudinal sides of the floor being left open. This fourth side is, however, closed when the malting-floor is in its normal position by a stationary partition 5, secured to metallic standards 6, arranged between the contiguous movable malting-floors and their suction-chambers e', the open side of each floor facing the floor next thereto, so that as each floor is elevated the grain may be transferred to the next floor. A tight joint between the edge of the perforated floor, along the open side, and the stationary partition 5 is obtained by means of a packing 7, of leather or equivalent material, secured to said floor and moving with it along said partition 5 when said floor is elevated. The standards 6 of the fixed partition 5 engage U iron braces 4, Fig. 6, bolted to the edges of end walls 3 and 3^a of the floor, and serve to guide said floor in its up and down movements, like braces or ties being secured centrally to said end walls to give the necessary strength or rigidity.

To each end girder of the floor-frames 1, on opposite sides of the central **U**-braces 4, is secured a lug or bearing 8, Figs. 5 and 6, with which engage the hooks n^2 of the lifter-rods 5 n' of the lifting mechanism presently to be described. The frame 1 of the movable malting-floors is so constructed as to bear evenly upon the face of the walls of the chambers e' below said floors, so as to form a tight joint 10 therewith.

The devices or mechanisms for elevating the malting-floors and transferring the grain from one to another are constructed and arranged as follows:

15 G indicates the carriage upon which these mechanisms are mounted, said carriage being supported by three pairs of wheels W traveling on the rails g' , hereinbefore referred to. At one end of the malting-chamber A is arranged the driving-shaft a for said carriage, said shaft carrying at opposite ends a belt-pulley P. At the opposite end of said chamber, and on opposite sides thereof, are arranged tension-pulleys P', over which travel the driving belts or ropes that propel the carriages and operate the lifting and transferring mechanisms.

The shaft a may be driven from any suitable prime motor, or more conveniently from 30 the motor that drives the exhaust-fan. The main driving-rope x is arranged as follows:

From the driving-pulley P the upper part of the rope x passes over a guide-pulley q on the carriage G, thence around the under side 35 of a driving-pulley Q, loosely mounted on the main driving-shaft of said carriage, and from the under side of said driving-pulley Q said upper part of rope x passes over a second guide-pulley q' , and then over the tension-pulley P'.

40 From the driving-pulley P the lower portion of rope x passes under pulley q , over pulley Q, under pulley q' , thence under tension-pulley P', said pulleys q Q q' having each two grooves for the purpose.

45 On the driving-shaft b of the carriage G is mounted a friction-clutch c between two bevel-pinions d g , both loose on said shaft and provided with cone-hubs, upon which the clutch 50 operates. As shown in Fig. 5, the bevel-pinion d has an extended tubular hub d' , to which is keyed the belt-pulley Q, so that when the clutch c is brought in engagement with the cone-hub of pinion d the shaft b is revolved in one direction. When, on the contrary, the 55 clutch c is brought in contact with the cone-hub of pinion g , said shaft will be rotated in a reverse direction through the medium of the intermediate pinion f , as shown in Figs. 60 5 and 7.

The clutch may be operated in any suitable manner—as, for instance, by means of the system of levers h and i , (shown in Fig. 7,) said lever h encompassing the friction-clutch.

65 The shaft b carries two bevel-pinions k , that mesh with bevel-wheels l , mounted on the up-

per end of short vertical shafts M, which shafts also carry a pinion m , that meshes with the toothed wheel n , whose hubs are screw-threaded interiorly, and in which hubs work the screw-threaded lifting-rods n' . These rods are arranged in pairs at opposite ends of the carriage and are connected by a rod o , Figs. 5 and 6, and are provided with the lifting-hooks n^2 , that engage the lugs or bearings 70 8, hereinbefore referred to.

By means of the mechanism described the malting-floors are elevated and lowered for transferring the grain from one floor to another and returning such floor to its normal 80 position.

Between the cheeks or lateral standards of the frame of the carriage G is arranged a conveyer L, whose buckets or scrapers L' extend 85 the full length of the malting-floor, and said conveyer is operated from the shaft of the guide-pulley q' , on which is mounted a belt-pulley q^2 , belted to a pulley q^3 on a shaft q^6 , mounted on the conveyer-frame K. The latter shaft carries a pinion q^4 , that meshes with a gear-wheel q^5 on the driving-shaft of the conveyer, as more plainly shown in Fig. 7, the direction of motion of the conveyer being indicated by arrow, Fig. 4. Motion in one or 90 the other direction over the series of malting-floors is imparted to the carriage G by means of the following mechanism:

A friction-clutch s , operated by a shifting-lever t , Fig. 5, is mounted on a short shaft S, 100 which shaft also carries a belt-pulley s' . The friction-clutch s is arranged to operate upon a friction-cone r , keyed to the short shaft of the intermediate bevel-pinion f , hereinbefore described. The belt-pulley s' is belted to a 105 pulley v' on a counter-shaft v , and on said shaft v , which extends across the carriage-frame, are mounted sprocket-wheels w , that are connected by chains w' , Figs. 5 and 6, to like sprocket-wheels w^2 on the driving-axle of 110 the right-hand pair of wheels W of the carriage G.

By means of the described mechanism the carriage can be moved in either direction on the rails g' by properly manipulating the 115 clutch-coupling s on shaft S.

It will be observed that the main driving-belt, through the medium of the intermediate mechanism, serves to propel the carriage to and fro on the rails g' to operate the conveyer 120 L and to elevate and lower the malting-floors. When one of these floors is to be elevated, the carriage is run over it, so that the hooks n^2 on the lifter-rods will engage the lugs or bearings 8 at opposite ends of the floor. The 125 clutch-lever i is now manipulated to bring the clutch c in contact with the cone-hub of pinion d , thus revolving the shaft b and bevel-wheels n through the intermediate gear l m to cause the rods n' to ascend through the 130 hubs of said wheels n until the floor has been elevated to the conveyer, when said floor will be in a position relatively to the next adjoining floor to transfer the grain from the

former to the latter, which is effected by the mechanism previously described, the elevator being set in operation the moment the clutch *c* is brought into engagement with the cone-hub of pinion *d*, the grain being scraped off the floor and transferred to the adjoining one below.

By a reversal of the clutch *c* the pinion *g* will be actuated through the medium of the intermediate pinion *f*, and the shaft *b* will be rotated in a reverse direction to lower the malting-floor. Finally, the clutch *s* may be brought into operation to move the carriage *G* over another malting-floor.

15 It will be readily understood that the conveyer and its operating mechanism may be dispensed with and the transfer effected by manual labor, in which case a suitable staging is secured to the carriage for the workmen.

20 Having described my invention, what I claim is—

1. In a malt-house, a plurality of adjacent vertically-movable perforated malting-floors inclosed on three sides, and a stationary partition interposed between the floors and forming the inclosing-wall for the open side of such floors, in combination with an elevating mechanism arranged above said floors and adapted to be moved from one floor to another and connected therewith, substantially as and for the purposes specified.

2. In a malt-house, a plurality of adjacent vertically-movable perforated malting-floors inclosed on three sides, and a stationary partition interposed between the floors and forming the inclosing-wall for the open side of such floors, and in combination therewith a conveyer or scraper arranged above said floors and operating to transfer the malt from one floor to another, substantially as and for the purposes specified.

3. In a malt-house, a plurality of adjacent vertically-movable perforated malting-floors inclosed on three sides, and a stationary partition interposed between the floors and forming the inclosing-wall for the open side of such floors, in combination with an elevating mechanism adapted to be connected to said floors, and a conveyer or scraper, both mounted on the same support and adapted to be moved to and fro above the malting-floors, substantially as and for the purposes specified.

4. In a malt-house, a plurality of adjacent vertically-movable perforated malting-floors inclosed on three sides, and a stationary partition interposed between the floors and forming the inclosing-wall for the open side of such floors, and in combination therewith a conveyer or scraper, a wheeled carriage therefor, an elevated way for said carriage, and a driving mechanism for the conveyer mounted on said carriage, substantially as and for the purposes specified.

5. In a malt-house, a plurality of adjacent vertically-movable perforated malting-floors inclosed on three sides, and a stationary partition interposed between the floors and form-

ing the inclosing-wall for the open side of such floors, and in combination therewith an elevated way, a wheeled carriage adapted to travel on said way, and an elevating mechanism mounted on said carriage for elevating the floors, substantially as and for the purposes specified.

6. In a malt-house, a plurality of adjacent and vertically-movable malting-floors comprising a rectangular frame, a perforated floor secured thereto, and vertical inclosing-walls arranged on one side and at opposite ends of said frame, in combination with a stationary partition arranged to close the fourth open side of the floor, substantially as and for the purposes specified.

7. In a malt-house, a plurality of adjacent and vertically-movable malting-floors comprising a rectangular frame, a perforated floor secured thereto, and vertical inclosing-walls arranged on one side and at opposite ends of said frame, in combination with a stationary inclosing-wall arranged to close the fourth open side of the floor, and a packing secured to the edge of said floor along the open side to form a tight joint with the stationary inclosing-wall, substantially as and for the purposes specified.

8. The combination, with a plurality of contiguous or adjacent vertically-movable perforated malting-floors provided with lugs or bearings *S* at opposite ends, of an elevated way, a carriage adapted to travel to and fro on said way, and a lifting mechanism comprising the screw-threaded hooked rods *n'*, the hooks of which are adapted to engage the lugs or bearings *S* of the floors, the bevel-wheels *n*, having interiorly-threaded hubs in which said rods work, and a driving-gear for driving said bevel-wheels, substantially as and for the purposes specified.

9. The combination, with a plurality of contiguous or adjacent vertically-movable perforated malting-floors, of an elevated way, a carriage adapted to travel to and fro on said way, a conveyer or scraper comprising an endless belt arranged to travel in a horizontal plane and provided with conveyer buckets or scrapers, mechanism for imparting motion to said belt, and an elevating mechanism for elevating the malting-floor to said conveyer mounted on said carriage, substantially as and for the purposes specified.

10. In a malt-house, a vertically-movable perforated malting-floor, a suction-chamber below said floor, an air-exhaust duct connected with said chamber, and a gravity-valve interposed in said connection, said valve having its stem in contact with the floor or a projection thereon when said floor is seated on the suction-chamber to hold the valve open, substantially as and for the purposes specified.

11. In a malt-house, a plurality of contiguous or adjacent vertically-movable malting-floors, a suction-chamber below each floor, an air-exhaust duct connected with said cham-

bers, a gravity-valve in said connections, said valves having their stems in contact with their respective malting-floors to hold the valve open when the floor is seated on the suction-chamber, an elevated way, a carriage adapted to travel to and fro on said way, and an elevating mechanism mounted on said carriage for elevating the floors, whereby, when a malting-floor is elevated, the valve will automatically close to cut off the communication between the suction-chamber and air-exhaust duct, substantially as and for the purposes specified.

12. In a malt-house, a malting-chamber, a series of contiguous or adjacent vertically-movable perforated malting-floors, and a stationary malting-floor at the end of the series, a withering-chamber adjacent to the malting-chamber, a perforated withering-floor in said chamber, and a suction-chamber arranged under each of said floors, and in combination therewith an air-duct in communication with the malting-chamber, a separate air-

supply for the withering-chamber, and an air-exhaust duct common to all the suction-chambers of the floors, substantially as and for the purposes specified.

13. In a malt-house, a substantially air-tight malting-chamber, a plurality of contiguous or adjacent vertically-movable perforated malting-floors, and a suction-chamber under each of said floors, in combination with an air-distributing duct provided with separate outlet-ports for each malting-floor, means for combining moisture with the air admitted, an air-exhaust duct, a separate connection between the suction-chamber of each malting-floor and said air-exhaust duct, and a valve in said connection, substantially as and for the purposes specified.

In testimony whereof I affix my signature in presence of two witnesses.

ERICH KASTEN.
